UNITED STATES PATENT OFFICE

102,989

DESIGN FOR TEXTILE FABRIC OR SIMILAR ARTICLE

Herman D. Mendelsohn, New York, N. Y.

Application September 10, 1936, Serial No. 64,796

Term of patent 3½ years

To all whom it may concern:

Be it known that I, Herman D. Mendelsohn, a citizen of the United States, residing at New York city, in the county of New York and State of New York, have invented a new, original, and ornamental Design for Textile Fabric or Similar Article, of which the following is a specification, reference being had to the accompanying drawing, forming a part thereof.

The figure is a plan view of the textile fabric showing my new design.

I claim:

The ornamental design for textile fabric or similar article, as shown.

HERMAN D. MENDELSON.
